UNITED STATES PATENT OFFICE

95,145

DESIGN FOR A VARIABLE SPEED ELECTRIC POWER UNIT

George T. Pfleger, Los Angeles, Calif.

Application December 11, 1933, Serial No. 50,036

Term of patent 14 years

To all whom it may concern:

Be it known that I, George T. Pfleger, a citizen of the United States, and a resident of the city of Los Angeles, in the county of Los Angeles and State of California, have invented a new, original, and ornamental Design for a Variable Speed Electric Power Unit, of which the following is a specification, reference being had to the accompanying drawing, forming part thereof, in which:

Figure 1 is a top plan view on a reduced scale of the unit embodying the invention;
Fig. 2 is a side elevation thereof; and
Fig. 3 is an end view thereof.

I claim:

The ornamental design for a variable speed electric power unit substantially as shown.

GEORGE T. PFLEGER.
